PRODUCTION OF OLEFINS

Marcel J. P. Bogart, Mamaroneck, N. Y., assignor to The Lummus Company, New York, N. Y., a corporation of Delaware

Application November 22, 1955, Serial No. 548,332

16 Claims. (Cl. 183—115)

This invention relates to the simultaneous recovery of olefins, particularly acetylene and ethylene from a hydrocarbon gas mixture and further relates to the efficient separation of these specific olefins from other close boiling constituents of the gaseous mixture.

As pointed out in my copending application, Serial Number 428,489, filed May 10, 1954, now abandoned, and entitled, "Acetylene Production," the high temperature cracking of hydrocarbons either of the normally liquid or normally gaseous type in a regenerative furnace or alternative methods for hydrocarbon pyrolysis results in a gaseous mixture which contains, in addition to the desired olefins, a plurality of compounds whose separation is both difficult and expensive. Furthermore, it is well known that the simultaneous recovery of ethylene and acetylene is particularly difficult because of the hazards of operating under temperatures and pressures which might otherwise be used for effective gas separation.

improved separation unit which permits effective separation and simultaneous production of high purity acetylene and ethylene in desired ratios with no substantial increase in cost of operation or through excessive duplication of facilities such as absorbers, strippers, heat exchangers, etc., as would result from conventional practice of separating and purifying the acetylene and ethylene by individually different process routes.

Further objects and advantages of my invention will appear from the following description thereof taken in conjunction with the attached drawings in which:

Figure 1 is a schematic process flow diagram for the production and recovery of high purity ethylene and acetylene; and

Figure 2 is a modified form of the process illustrated in Figure 1.

In a conventional hydrocarbon cracking process in which a selected hydrocarbon feed is introduced into a high temperature furnace or other pyrolysis gas generator, 20 a cracked gas is obtained having a composition which may vary considerably depending upon the conditions at which the cracking is carried out and the nature of the feed used.

Table I, below, gives analyses of typical cracked gases obtained by the pyrolysis of such light hydrocarbons as ethane and propane. The high-temperature regenerative cracking was carried out at substantially $\frac{1}{2}$ atmosphere absolute total pressure, with steam dilution, and temperatures ranging from 1800° to 2300° F. The conventional cracking was carried out in a tubular furnace at slightly above atmospheric pressure, minor quantities of dilution steam, and temperatures ranging from 1470 to 1550° F.

In accordance with my invention, I prefer to first remove more hazardous and deleterious compounds such as diacetylene, water, and tarry materials from a gas mixture including ethylene and acetylene as set forth in my prior application and then to make the customary separation of lower boiling materials from C₂ hydrocarbons and higher fractions. Thereafter, the ethylene-acetylene mixture is made available for separation. Under prior practice it has been found that the partial pressure of acetylene under customary refluxing procedure in removal of combined C₂ hydrocarbons by distillation may become too great and proceed into such a range that the operation is considered hazardous.

It is a principal object of my invention to provide an

A comparison of the cracked gas compositions given in Table I indicates a wide range in the ratio of quantities of acetylene and ethylene produced by regenerative cracking, or combinations of regenerative and tubular cracking. The commercially important operations shown in Table I demonstrate a variation in this ratio of nearly a thousand-fold. In any event, the cracked gas composition for each cracked gas of Table I, as fed to my recovery system may generally contain, in addition to varying quantities of hydrogen, carbon dioxide, carbon monoxide, methane, ethylene and acetylene, a considerable amount of homologs of acetylene, such as methylacetylene, diacetylene, vinylacetylene, ethylacetylene, and divinylacetylene. Prior to treatment in my recovery system, such

a gas stream on removal from the pyrolysis unit is generally passed through quench apparatus to remove tarry materials and other undesirable components which have a tendency to foul processing equipment and generally make the recovery of acetylene and ethylene more difficult. Following the quench, the gas mixture is introduced to my recovery system.

Referring to Figure 1, a gaseous hydrocarbon mixture to be cracked is introduced into pyrolysis units 10 and 11 through lines 12 and 13 respectively. These high temperature cracking furnaces or other units for producing pyrolysis gas may be operated if desired so that the cracked gas mixture issuing from unit 10 contains a predominant quantity of acetylene relative to ethylene and the cracked gas mixture issuing from unit 11 contains a predominant quantity of ethylene relative to acetylene. The relative volumes of gas fed to these units and their operating temperatures and pressures determine the eventual relative quantity of high purity acetylene and ethylene products. The gases issuing from units 10 and 11 in lines 14 and 15, respectively, are water quenched at 16 and 17, respectively, with water for quenching provided through line 18. The quenching water, including tarry materials, is removed through lines 19 and 20.

To provide the predominance of acetylene in the product gas of unit 10, it has been found in a regenerative furnace type of pyrolysis unit that an absolute pressure of approximately $\frac{1}{2}$ atmosphere and a temperature range of between 1785 and 2265° F. are required; while to economically provide a predominance of ethylene relative to acetylene in unit 11, an absolute pressure of not below 1 atmosphere and a temperature range of from 1470 to 1550° F. are required. A vacuum pump 21 is provided in line 14 to boost the pressure of the cracked gas in such line to near atmospheric pressure, where it equals the pressure of the cracked gas in line 15. Thereafter, both cracked gas mixtures are introduced into a gas holder 22 and subsequently pass through line 23 to compressor 24. The combined cracked gases containing both acetylene and ethylene are raised to about 100-300 p. s. i. g. in compressor 24. The limitation of pressure applied to the cracked gases by the compressor is a function of the acetylene content of the gas, where the hazards of handling this reactive component dictates the limit in maximum partial pressure of acetylene to about 1.0 to 2.5 atmosphere absolute. This is in contrast to straight ethylene operations wherein pressures of 500-750 p. s. i. g. might be used in the absence of substantial quantities of acetylene.

The compressed gas in line 25 is cooled by direct or 50 indirect heat exchange with water in cooler 26 to a temperature above the hydrate formation point, with allowance made for the removal of any condensed water. The cooled cracked gas in line 25 is then introduced to absorber 27 which acts as a preabsorber for diacetylene. 55 Diacetylene, which is among the most soluble of the acetylene compounds, is removed by absorption in a small quantity of solvent introduced through line 28 at the top of the absorption section 27a. The solvent used, such as dimethylformamide, is highly selective for higher 60 homologs of acetylene and may also serve to remove remaining water and heavy hydrocarbons in the feed gas.

The quantity of acetylene absorbed simultaneously with the diacetylene is of the order of a few percent of that in the gas fed to the absorber by line 25. This potential loss of valuable product may be minimized, if desired, by the addition of stripping section 27b to absorber 27 and introduction of a relatively small quantity of stripping gas at the bottom of the stripping section by line 29. This stripping gas is preferably a recycled quantity of the nearly acetylene-free residual gas produced in the system. Both the absorption and stripping sections of absorber 27, as well as subsequent towers, may be provided with packing, bubble-cap or perforated trays, or any well-known device to promote good contacting between the gas and the liquid. To obtain near total re-

moval of the diacetylene by the solvent, absorber 27 is operated essentially at the compressor discharge pressure of 100 to 300 p. s. i. g. While certain economies may be obtained by refrigerating the solvent input and the 5 feed gas, this absorber is normally operated around 100° F.

The top of absorber 27 may be equipped with a water wash section 27c to prevent the loss of solvent overhead, clean wash water being introduced through line 30. The 10 water scrubber effluent 31 and tower bottoms 32 are combined and sent to a flash separator 33 operating at near atmospheric pressure, where the combination of dilution and reduction in pressure releases most of the absorbed gas, including diacetylene, which may then be 15 conveniently disposed of by recycling in line 34 to furnace 10. Such water-washing operations, however have the disadvantage of nullifying any dehydrating action of the solvent. In such cases I prefer to recover any solvent 20 carried out of the top of the absorber by refrigerating the absorber off gas, and removing condensed solvent therefrom for return to the absorption system.

The overhead gas leaving the preabsorber in line 35 contains most of the acetylene and ethylene and substantially all other gaseous components of the cracked gas 25 which are less soluble than diacetylene. The gases of line 35 are cooled in exchanger 36 and sent to the main absorber 37 wherein the C₂ hydrocarbons and heavier components are absorbed in a refrigerated lean oil stream introduced through line 38. For this lean oil I prefer a light hydrocarbon in the propane-gasoline range. The lean oil stream entering absorber 37 through line 38 is circulated within the system as described hereinafter. The charge stock to the plant in line 39 may be used as supplementary sponge oil if desired and is then introduced 30 to the main absorber through line 40 and a suitable refrigerated heat exchanger 41. Charge stocks too volatile in character to be introduced to the system by line 39 are fed directly to the furnaces by line 39a. The inefficiency of absorption of C₂ hydrocarbons at 100-300 p. s. i. g. (as against normal practice in ethylene plants of 500 p. s. i. g. or higher) is counteracted by the introduction of the absorption oils to absorber 37 in lines 38 and 40 at temperatures below 60° F. Thus energy previously required to compress the absorber feed gas up to 500 p. s. i. g. is transferred to refrigerated compressors cooperating with refrigerated chillers 41 and 42 to obtain the same relative overall efficiency. The main absorber is provided with suitable contact devices in the absorption and stripping sections 37a and 37b, respectively. Stripping gas is provided by reboiler 43, in line 44, heated by any desirable medium, such as steam or hot lean oil, and serves as final removal of components less soluble than acetylene and ethylene. Gases lighter than acetylene leave tower 37 in line 45.

The main absorber bottoms comprising acetylene, ethylene, and heavier hydrocarbons from the furnace effluent, dissolved in lean oil, are removed through line 46 and are sent by pump 46a to stripping tower 47. This distillation tower is provided with a stripping section 47a, reboiler 48 in line 49 and a rectifying section 47b which is charged with reflux comprising substantially a mixture of nearly pure acetylene and ethylene in admixture or nearly pure ethylene, as will hereinafter be described. The stripping tower 47 operates to give a C₂ hydrocarbon cut overhead which is partially condensed in overhead condenser 50 to provide reflux for the tower in line 55a.

The stripper bottoms in line 51 split at valve 52 into a first portion which becomes the main absorber lean oil stream 38 and a second portion in line 53 which passes through a vaporizer 54 and line 39a to provide the furnace charge in lines 12 and 13 when using the charge stock as sponge oil. Otherwise, the entire bottoms in line 51 are returned to the top of main absorber 37 except for a small quantity that may be redistilled

or sent to the cracking furnaces for prevention of build-up of heavy components.

As heretofore mentioned, the overhead from stripper 47 will be predominantly ethylene and acetylene, contaminated with any ethane and carbon dioxide in the cracked gas feed, and containing traces of methane and C₃+ hydrocarbons. This overhead mixture in line 55, after passage through overhead partial condenser 50 is passed to an acetylene absorption tower 56 where a separation is made between ethylene and acetylene by absorption of the acetylene in a selective solvent introduced by line 57. The solvent employed is generally the same as that used in absorber 27, such as dimethylformamide. Tower 56 functions as a fractionating absorber and utilizes a stripping section 56a, which is supplied with suitable reboil heat by reboiler 58 in line 59. It is thus possible to make a sharp separation between the ethylene, which is removed overhead through line 60, and a bottoms fraction removed through line 61 containing the acetylene dissolved in solvent. The overhead ethylene product may be further purified as desired to remove any ethane and carbon dioxide content therein. This overhead is maintained virtually free of acetylene in a final contact by the circulation of a redistilled stream of high purity refrigerated solvent introduced to tower 56 through line 62. The bottoms from column 56 are depressurized and heated in flash tank 63 to release their acetylene content which may then be passed through line 64 to cooler 65 to condense out any vaporized solvent and become the relatively pure acetylene product from the plant. If desired, heat may be introduced to the flash tank 63 by reboiler 66 in line 67. The solvent is removed through line 68 and passed through cooler 69. This cooled solvent is returned as the desired solvent of line 28 for introduction to the diacetylene preabsorber 27. A portion of the solvent of line 28 passes through line 57 to a refrigerated chiller 70 wherein it is cooled to below 60° F. and then introduced to absorber 56.

The wet solvent removed from the flash separator 33 through line 71 is redistilled in fractionating column 72, which is a conventional distillation tower. Column 72 is supplied with reboil heat by reboiler 73 in line 74. A water cooled condenser 75 is provided in overhead line 76 of tower 72 for condensing water as an overhead product which leaves the system in line 77. A portion of the overhead condensate is returned as reflux through line 78. Non-volatile impurities and heavy ends are eliminated from the solvent in line 71 in feed vaporizer 79. The bottoms passing from column 72 in line 80 constitute repurified solvent which is cooled to below 60° F. in refrigerated exchanger 81 before being sent to the top of column 56. If necessary, a quantity of solvent greater than that in the bottoms from tank 33 may be redistilled in column 72 by use of jumper feed line 82. The fractionating absorber 56 is operated preferably near atmospheric pressure for reasons of safety and the stripper 47 is normally operated so that the acetylene partial pressure of the overhead gas is maintained in a safe region.

The system as described thus far illustrates the simultaneous production of pure acetylene and ethylene wherein the ratio of acetylene to ethylene in overhead stream 55 of tower 47 is less than one-third. Operation above a one-third ratio of acetylene to ethylene at this point would involve producing an acetylene-ethylene overhead stream having an acetylene partial pressure approaching the point of hazardous operation. Where it is desired to obtain an acetylene to ethylene ratio of one-third or greater, my recovery system may be modified as illustrated in Figure 2. In such operation, the system up to and including stripper 147 is identical to that of Figure 1. In operation streams 138, 153, 151 and 146 contain fluids identical with those in streams 38, 53, 51 and 46 of Figure 1. Overhead stream 155 from tower 147

likewise contains a mixture of ethylene and acetylene similar to that in line 55 of Figure 1. However, such stream is forwarded directly to fractionating absorber 156 without having any portion condensed and returned as reflux to tower 147. A sharp separation between the ethylene and acetylene in line 155 is again accomplished in tower 156 by selective absorption of the acetylene in solvent, which is removed as bottoms stream 161. The overhead stream 160 comprising substantially pure ethylene from tower 156 is divided at valve 190 whereby a portion of such ethylene overhead is passed through line 191, compressor 192 and refrigerated condenser 193 to provide a reflux of nearly pure ethylene for the stripping tower 147. The overhead gas from tower 147 is then 10 the acetylene product diluted by both the ethylene product and the ethylene recirculated as reflux and introduced in line 191. The fractionating absorption tower 156 is operated preferably under atmospheric conditions. By 15 passing only ethylene as reflux to tower 147, such tower 20 may be safely operated at about 14 atmospheres. The remainder of the ethylene in line 160 becomes the relatively high purity ethylene product of the modified system. The relative quantity of ethylene product to acetylene products is lower in this modified form of my invention; however, economies in operation of stripper 147 are obtained by operating at a higher pressure and higher 25 temperature. In this modified system, it may be likewise desirable to introduce a repurified portion of solvent to the fractionating absorber 156 through line 162 and 30 refrigerated chiller 181.

The bottoms of the fractionating absorber 156 are depressurized as described heretofore and passed through line 161 into flash tank 163 to release their acetylene content. Relatively pure acetylene vapors may be cooled 35 at 165 in line 164 to condense out solvent and become the acetylene product from the plant. If desired, heat may be introduced in the flash tank 163, by reboiler 166 in line 167 and the solvent removed through line 168, passed through cooler 169 and returned as the desired solvent in lines 128 and 157.

The alternative modifications of my invention provide for highly efficient separation and simultaneous production of high purity acetylene and ethylene products in any desired ratio.

Table II is an illustration of the operating requirements of the process route depicted in Fig. 1 for a pyrolysis, gas of composition as given by Case E of Table I, wherein a ratio of acetylene to ethylene of 1:4 is produced in the regenerative cracking unit of the plant.

TABLE II

55 Summary of tower operating conditions

60	Designation	Pressure, p. s. i. g.	Temperature, Top, °F.	Net Feed, ¹ Moles	Absorption Solvent, ² Moles	Partial Pressure of C ₂ H ₂ in O. H., Atmospheres
65	Diacetylene Absorber (27)	245	100	100.0	20.0	1.03
	Main Absorber (37)	235	-40	98.5	102.0	1.01
	Stripper (47)	180	-40	37.3	59.0	2.20
70	Acetylene Absorber (56)	0	-40	37.2	144.0	.0001
	Solvent Still (72)	0	212			

¹ Does not include absorption solvent.

² Or reflux.

Operation of the unit according to the conditions of Table II produces product streams of the purities indicated in Table III.

7
TABLE III

Total.....	100.00	100.00

The acetylene and ethylene product streams may be further purified by well-known conventional means such as CO_2 removal by caustic wash, if desired. It may be noted from an inspection of Table II that acetylene to ethylene product ratios greater than 1:4 will exceed the 2.2 atmospheres maximum acetylene partial pressure noted in Table II. For acetylene to ethylene ratios greater than the range of 1:4 to 1:2 I prefer to use the alternate processing route shown in Fig. 2, wherein the purified ethylene product stream is partly returned to stripper 147 as the liquid reflux for that tower. As an example of this alternate operation, the pertinent operating requirements for the unit are given in Table IV, final purities of the acetylene and ethylene products will be as given above except that the methane, ethane, and carbon dioxide contaminants will vary with their content in the pyrolysis gas. Table IV below also includes the pertinent information for the feed stock of Case E so that a comparison may be made with the processing requirements for the same stock by the process route of Fig. 1, as given in Table III.

While I have shown and described preferred forms of my invention, I am aware that variations may be made thereto and I, therefore, desire a broad interpretation of my invention within the scope of the disclosure herein and the following claims.

I claim:

1. A process for simultaneously recovering substantially pure acetylene and pure ethylene from a gaseous mixture obtained by the high temperature cracking of a hydrocarbon feed, which comprises passing said gaseous mixture comprising acetylene, ethylene, and diacetylene

65 3. The process as claimed in claim 2 wherein the third contact solvent after separation from the product acetylene is recirculated in part to provide a portion of the solvent for said third contact and in part to provide solvent for said first contact.

70 4. A process for simultaneously recovering substantially pure acetylene and pure ethylene from a gaseous mixture obtained by the high temperature cracking of a hydrocarbon feed, which comprises passing said gaseous mixture comprising acetylene, ethylene, and diacetylene 75 through a first contact with a sufficient amount of a se-

through a first contact with a sufficient amount of a selective solvent to remove substantially all of the diacetylene, passing said gaseous mixture through a second contact with a selective solvent of sufficient amount to absorb substantially all of the acetylene and ethylene in said mixture, separating the absorbed gas from the solvent of said second contact, passing said separated gas through a third contact with a selective solvent of sufficient amount to absorb substantially all of the acetylene therefrom, withdrawing as product substantially all of the pure ethylene passing through said third contact solvent, and separating as product substantially all of the acetylene absorbed by said third contact solvent.

15 2. A process for simultaneously recovering substantially pure acetylene and pure ethylene from a gaseous mixture obtained by the high temperature cracking of a hydrocarbon feed, which comprises passing said gaseous mixture comprising acetylene, ethylene, and diacetylene through a first contact with a sufficient amount of a selective solvent to remove substantially all of the diacetylene, passing said gaseous mixture through a second contact with a lean oil of sufficient amount to absorb substantially all of the acetylene and ethylene in said mixture, separating the absorbed gas including acetylene and ethylene from the lean oil of said second contact, passing said separated gas through a third contact with a selective solvent of sufficient amount to absorb substantially all of the acetylene therefrom, withdrawing as product substantially all of the pure ethylene passing through said third contact solvent, and separating as product substantially all of the acetylene absorbed by said third contact solvent.

lective solvent to remove substantially all of the diacetylene, passing said gaseous mixture through a second contact with a selective solvent of sufficient amount to absorb substantially all of the acetylene and ethylene in said mixture, separating the absorbed gas from the solvent of said second contact, passing said separated gas through a third contact with a major portion of refrigerated selective solvent of sufficient amount to absorb substantially all of the acetylene therefrom and thence with a minor portion of relatively high purity selective solvent to absorb the remainder of acetylene therefrom, withdrawing as product substantially all of the pure ethylene passing through said third contact, and separating as product substantially all of the acetylene absorbed by said third contact solvents.

5. The process as claimed in claim 4 wherein the major portion of selective solvent in the third contact is refrigerated to a temperature of below 60° F.

6. The process as claimed in claim 4 wherein the major and minor portions of solvent including absorbed acetylene of the third contact are combined prior to separation of said acetylene from said third contact solvents.

7. A process for simultaneously recovering substantially pure acetylene and pure ethylene from a gaseous mixture obtained by the high temperature cracking of a hydrocarbon feed, which comprises passing said gaseous mixture comprising acetylene, ethylene, and diacetylene through a first contact with a sufficient amount of a selective solvent to remove substantially all of the diacetylene, passing said gaseous mixture through a second contact with a selective solvent of sufficient amount to absorb substantially all of the acetylene and ethylene in said mixture, separating the absorbed gas from the solvent of said second contact and refluxing said separation with a portion of such separated gases, passing the remainder of said separated gas through a third contact with a selective solvent of sufficient amount to absorb substantially all of the acetylene therefrom, withdrawing as product substantially all of the pure ethylene passing through said third contact solvent, and separating as product substantially all of the acetylene absorbed by said third contact solvent.

8. A process for simultaneously recovering substantially pure acetylene and pure ethylene from a gaseous mixture obtained by the high temperature cracking of a hydrocarbon feed, which comprises passing said gaseous mixture comprising acetylene, ethylene, and diacetylene through a first contact with a sufficient amount of a selective solvent to remove substantially all of the diacetylene, passing said gaseous mixture through a second contact with a lean oil of sufficient amount to absorb substantially all of the acetylene and ethylene in said mixture, separating the absorbed gas including acetylene and ethylene from the lean oil of said second contact and refluxing said separation with a portion of such separated gases, passing the remainder of said separated gas through a third contact with a selective solvent of sufficient amount to absorb substantially all of the acetylene therefrom, withdrawing as product substantially all of the pure ethylene passing through said third contact solvent, and separating as product substantially all of the acetylene absorbed by said third contact solvent.

9. A process for simultaneously recovering substantially pure acetylene and pure ethylene from a gaseous mixture, obtained by the high temperature cracking of a hydrocarbon feed, which comprises passing said gaseous mixture comprising acetylene, ethylene, and diacetylene through a first contact with a sufficient amount of a selective solvent to remove substantially all of the diacetylene, passing said gaseous mixture through a second contact with a selective solvent of sufficient amount to absorb substantially all of the acetylene and ethylene in said mixture, separating the absorbed gas including acetylene and ethylene from the solvent of said second contact and

refluxing said separation with a portion of the separated gases, maintaining a partial pressure of acetylene in said separation of about 1.0 to 2.5 atmospheres absolute, passing the remainder of said separated gas through a third contact with a selective solvent of sufficient amount to absorb substantially all of the acetylene therefrom, withdrawing as product substantially all of the pure ethylene passing through said third contact solvent, and separating as product substantially all of the acetylene absorbed by said third contact solvent.

10. The process as claimed in claim 9 wherein the ratio of acetylene to ethylene products is less than $\frac{1}{4}$ to $\frac{1}{2}$.

11. A process for simultaneously recovering substantially pure acetylene and pure ethylene from a gaseous mixture obtained by the high temperature cracking of a hydrocarbon feed, which comprises passing said gaseous mixture comprising acetylene, ethylene, and diacetylene through a first contact with a sufficient amount of a selective solvent to remove substantially all of the diacetylene, passing said gaseous mixture through a second contact with a selective solvent of sufficient amount to absorb substantially all of the acetylene and ethylene in said mixture, separating the absorbed gas from the solvent of said second contact, passing said separated gas through a third contact with a selective solvent of sufficient amount to absorb substantially all of the acetylene therefrom, withdrawing as product substantially all of the pure ethylene passing through said third contact solvent, recirculating a portion of said pure ethylene as reflux to said separation of absorbed gas from said second contact solvent, and separating as product substantially all of the acetylene absorbed by said third contact solvent.

12. A process for simultaneously recovering substantially pure acetylene and pure ethylene from a gaseous mixture obtained by the high temperature cracking of a hydrocarbon feed, which comprises passing said gaseous mixture comprising acetylene, ethylene, and diacetylene through a first contact with a sufficient amount of a selective solvent to remove substantially all of the diacetylene, passing said gaseous mixture through a second contact with a lean oil of sufficient amount to absorb substantially all of the acetylene and ethylene in said mixture, separating the absorbed gas including acetylene and ethylene from the lean oil of said second contact, passing said separated gas through a third contact with a selective solvent of sufficient amount to absorb substantially all of the acetylene therefrom, withdrawing as product substantially all of the pure ethylene passing through said third contact solvent, recirculating a portion of said pure ethylene as reflux to said separation of absorbed gas from said second contact solvent, and separating as product substantially all of the acetylene absorbed by said third contact solvent.

13. A process for simultaneously recovering substantially pure acetylene and pure ethylene from a gaseous mixture obtained by the high temperature cracking of a hydrocarbon feed, which comprises passing said gaseous mixture comprising acetylene, ethylene, and diacetylene through first contact with a sufficient amount of a selective solvent to remove substantially all of the diacetylene, passing said gaseous mixture through a second contact with a selective solvent of sufficient amount to absorb substantially all of the acetylene and ethylene in said mixture, separating the absorbed gas from the solvent of said second contact, passing said separated gas through a third contact with a selective solvent of sufficient amount to absorb substantially all of the acetylene therefrom, withdrawing as product substantially all of the pure ethylene passing through said third contact solvent, recirculating a sufficient amount of said pure ethylene as reflux to said separation of absorbed gas from said second contact solvent whereby the partial pressure of acetylene in said separation is maintained at about 1.0 to 2.5 atmospheres absolute, and separating as product substantially all of the acetylene absorbed by said third contact solvent.

14. The process as claimed in claim 13 wherein the ratio of acetylene to ethylene is greater than $\frac{1}{4}$ to $\frac{1}{2}$.

15. A process for simultaneously recovering substantially pure acetylene and pure ethylene which comprises continuously cracking a hydrocarbon feed under conditions to produce a gaseous mixture comprising a predominance of acetylene, continuously cracking a hydrocarbon feed under conditions to produce a gaseous mixture including a predominance of ethylene, combining the gaseous mixtures, passing said combined gaseous mixture including acetylene, ethylene, and diacetylene through a first contact with a sufficient amount of a selective solvent to remove substantially all of the diacetylene, passing said combined gaseous mixture through a second contact with a selective solvent of sufficient amount to absorb substantially all of the acetylene and ethylene in said mixture, separating the absorbed gas from the solvent of said second contact, passing said separated gas through a third contact with a selective solvent of sufficient amount to absorb substantially all of the acetylene 15

therefrom, withdrawing as product substantially all of the pure ethylene passing through said third contact solvent, and separating as product substantially all of the acetylene absorbed by said third contact solvent.

16. The process as claimed in claim 15 wherein said first continuous cracking is carried on in a regenerative furnace at an absolute pressure of approximately $\frac{1}{2}$ atmosphere and a temperature of between 1785° F. and 2265° F. and said second continuous cracking is carried on in a furnace at an absolute pressure of at least 1 atmosphere and a temperature of between 1470° F. and 1550° F.
